Patented June 10, 1958

183,012

AUTOMOBILE GRILLE

Friedrich K. H. Nallinger and Rudolf E. Uhlenhaut, Stuttgart, Germany, assignors to Daimler-Benz Aktiengesellschaft, Stuttgart-Unterturkheim, Germany

Original application February 5, 1954, Serial No. 28,870, now Design Patent No. 176,278, dated December 6, 1955. Divided and this application August 15, 1955, Serial No. 37,468

Term of patent 14 years

Claims priority, application Germany November 14, 1953

(Cl. D14—18)

Figure 1 is a perspective view of an automobile grille embodying our new design; and

Figure 2 is a front elevational view thereof shown in reduced scale.

The dotted line disclosure of an automobile is shown only for purpose of illustration.

This application is a divisional application of our co-pending design application Serial Number D. 28,870, filed on February 5, 1954, which is now Design Patent 176,278, issued on December 6, 1955.

We claim:

The ornamental design for an automobile grille, substantially as shown and described.
